UNITED STATES PATENT OFFICE.

MAXIMO GUIDOTE, OF MANILA, PHILIPPINE ISLANDS.

COMPRESSED-AIR RIFLE.

Application filed November 28, 1925. Serial No. 72,011.

This invention contemplates the provision of a rifle adapted to be operated by compressed air, the invention residing in the novel construction, combination and arrangement of parts hereinafter described and particularly pointed out in the appended claims.

In the drawing forming part of this application, like numerals of reference indicate similar parts in the several views, and wherein:

Figure 1 is a side elevation of the rifle constructed in accordance with the present invention.

Figure 2 is a fragmentary view showing by dotted lines the active position of the reloading mechanism, and by full lines the position of said mechanism after the rifle has been fired.

Figure 3 is an enlarged fragmentary view partly in section showing the position of the compressed air chamber and valve with relation to the trigger.

Figure 4 is a longitudinal section through the compressed air chamber and valve which controls communication between said air chamber and the barrel of the rifle.

Figure 5 is an enlarged fragmentary view showing the position of the trigger controlled mechanism after the rifle has been fired.

Figure 6 is a sectional view on line 6—6 of Figure 5.

Figure 7 is a view similar to Figure 5 showing the arrangement of the trigger controlled mechanism prior to the firing of the rifle.

Referring to the drawings in detail, 10 indicates the butt of the rifle, while the barrel therefor is indicated at 11. Arranged adjacent the barrel is a magazine chamber 12 for the reception of the projectiles 13, the latter being singly fed into the bore of the barrel 11 through the instrumentality of a follower 14 actuated by a spring 15 arranged in a compartment formed in the chamber 12, as clearly illustrated in Figure 7. The follower 14 is provided with a knob or handle 16 which slides through a slot 17, so that the follower can be easily and conveniently retracted against the tension of the spring 15, as the occasion may require. Each projectile 18 is fired or projected from the rifle through the instru-

mentality of a plunger 19, the latter being actuated by compressed air admitted to a tube 20 in which the plunger 19 is mounted for sliding movement. This tube 20 communicates with a valve casing 21 clearly shown in Figure 4, and in which casing is arranged a valve seat 22 normally engaged by a valve 23. This valve is carried by a sliding rod 24 about which is arranged a coiled spring 25, one end of which bears against the valve, while the other end bears against the adjacent end of the compressed air chamber 26, and is utilized to hold the valve normally seated. The valve casing is threaded into a chamber 27 arranged directly beneath the tube 20 and communicating with the latter, while the sliding rod 24 of this valve projects within the chamber 27 to be actuated by a trigger controlled mechanism in a manner to be hereinafter described. As shown in Figure 4, the compressed air chamber 26 is arranged in end to end relation with the valve casing 21, and has an opening in one end thereof to receive the sliding rod 24 of the valve structure. This same end of the compressed air chamber 26 is also provided with openings 28 to allow the compressed air from the chamber 26 to enter the valve casing, and subsequently pass around the valve into the tube 20, when, of course, the valve 23 is opened. The compressed air chamber 26 is equipped with a suitable valve 29, through which compressed air is adapted to be pumped into the chamber 26, as will be readily understood.

The trigger controlled mechanism above referred to includes a short rod 30 mounted for sliding movement within the chamber 27 and normally bearing against the adjacent end of the sliding valve rod 24. This rod 30 projects forwardly of the casing 27 and is adapted to be actuated by a cam 31 pivoted as at 32 and formed with a nose-like extremity 33 for a purpose to be presently described. A shaft 34 has mounted thereon a tumbler 35, the latter being formed with spaced projections 36 and 37, respectively, which projections cooperate with the nose-like extremity 33 of the cam to assist in operating the latter. The tumbler 35 is formed with a lug 38 which is connected by a link 39 with one branch of a spring 40, the latter being of substantially U-shaped

formation with the said branch 41 susceptible of movement with relation to the other branch, indicated at 42.

Cooperating with the lug 38 of the tumbler 35 is a lever 43, for holding the tumbler in the position shown in Figure 7 with the rifle charge, while the lever 43 is maintained in this position against the influence of a spring 44 by means of a lever 45, one end of which contacts the adjacent end of the lever 43, while the other end of which bears against the adjacent extremity 46 of the trigger 47. In this position of parts the spring 40 is also under tension, so that when the trigger is operated to effect a release of the tumbler 35, the limb 41 of the spring 40 functions to operate the tumbler in the manner to initially impart movement to the cam 31. This cam is forcibly operated by means of a spring 48 to slide the rod 30 against the rod 24 of the valve, thereby very quickly opening the valve to allow a charge of compressed air to pass into the chamber 27, and thence into the tube 20 to operate the plunger 19.

Assuming that the parts are arranged in the manner shown in Figure 7, wherein it will be noted that one of the projectiles 18 is arranged directly in advance of the plunger 19, it is only necessary to pull the trigger 47 in order to fire the rifle, or in other words project the projectile 18 therefrom. When the trigger 47 is pulled it pushes down on the adjacent end of the lever 45, which lever is pivoted at a point between its ends, thereby rocking the lever 43 in a direction to separate the lever from the tumbler 35. At this moment the spring 40 expands, whereupon the limb 41 of said spring quickly and forcibly assumes the position illustrated in Figure 5, thereby turning the tumbler in the direction of the cam 31. As the tumbler is rotated in this direction, the projection 36 contacts the nose-like extension 33 of the cam 31, thereby turning the cam together with the assistance of the spring 48 against the rod 30, which rod in turn opens the valve 23 in the manner above described, and allows a charge of compressed air to find its way into the tube 20, operating the plunger 19. The position occupied by the various parts of this mechanism, after the rifle has been fired, is clearly illustrated in Figure 5. It will be noted in this figure that as the branch 41 of the spring 40 expands, it is brought into contact with a spring 50 to cushion the movement of said branch 41, and at the same time place the spring 50 under tension so that the latter will assist in returning the mechanism to the position shown in Figure 7 incident to the recharging of the rifle.

The recharging mechanism includes a hand grip 51 mounted for sliding movement on a rod 52 and connected by means of a plate 53 with a sliding arm 54. This arm

54 has one end connected with a link 55 which in turn is connected with the shaft 34 upon which is mounted the tumbler 35, so that when the recharging mechanism is operated, it functions to rotate the shaft 34 in an opposite direction. During this rotation of the shaft 34 the pointed projection 37 of the tumbler engages the nose-like extension 33 of the cam 31, and thereupon moves the cam from the position shown in Figure 5 to the position illustrated in Figure 7. Consequently, the branch 41 of the U-shaped spring 40 is also returned from the position shown in Figure 5 to the position shown in Figure 7, and the lever 43 again arranged to engage the lug 38 of the tumbler to maintain the parts in the position shown in Figure 7. While these parts are being arranged in the manner just described, the plunger 19 is also being retracted into the tube 20 to the position which it occupies in Figure 7, and this is accomplished by the means clearly shown in Figure 2. For this purpose I employ a bell crank lever which is pivoted as at 56, and which lever has its short branch 57 disposed to be engaged by a member 58 carried by the plunger 19 when the rifle has been fired. When the rifle is charged the bell crank lever assumes the position shown by dotted lines in Figure 2, and when the rifle is fired, the member 58 carried by the plunger 19 engages the short branch 57 of said bell crank lever and moves it to the position shown by full lines in Figure 2. The movement of this lever in this direction is cushioned by a spring 59 carried by the other branch 60 of said lever and adapted to contact a stop pin 61. Also carried by the shaft 34 upon which the tumbler 35 is mounted is a finger 62, which cooperates with the branch 60 of the bell crank lever to retract the plunger 19 while the rifle is being recharged in the manner above described. When the rifle is fired this finger 62 is moved to the position it occupies in full lines in Figure 2, being limited in its movement in this direction by a stop pin 63. Now, when the recharging mechanism is operated the shaft 34 is turned in the manner above described, and during this rotation of the shaft 34 the finger 62 is brought into contact with the adjacent branch 60 of the bell crank lever, rocking the latter upon its pivot 56, and shifting said lever to the position shown by dotted lines in Figure 2, during which operation the plunger 19 is retracted from the position shown in Figure 5 to the position it occupies in Figure 7. It will be noted upon inspection of Figure 3 that the compressed air chamber and valve casing are preferably arranged within the butt 10 of the rifle.

While it is believed that from the foregoing description the nature and advantages of the invention will be readily apparent, I

desire to have it understood that I do not limit myself to what is herein shown and described, and that such changes may be resorted to when desired as fall within the scope of what is claimed.

Having thus described the invention, what is claimed as new, is:—

1. In a rifle of the character described, a barrel, a magazine, means for singly feeding projectiles from the magazine to said barrel, a compressed air receiving chamber, a tube establishing communication between said chamber and barrel, a plunger operating in said tube, a valve controlling said communication and including a sliding rod, means for opening said valve and including a cam, a tumbler designed to operate said cam, means for operating said tumbler, means including a trigger for normally holding said tumbler cocked, and means for reloading the rifle.

2. In a rifle of the character described, a barrel, a magazine, means for singly feeding projectiles from the magazine to said barrel, a compressed air receiving chamber, a tube establishing communication between the chamber and barrel, a valve controlling said communication, a plunger adapted to be actuated by compressed air and operable in said tube and barrel, means for opening said valve including a cam, resilient means for forcibly operating said tumbler, trigger actuated means for effecting a release of said resilient means, and means for reloading the rifle.

3. In a rifle of the character described, a

barrel, a magazine, means for singly feeding projectiles from the magazine into the barrel, a compressed air receiving chamber, a tube establishing communication between said chamber and barrel, a plunger slidable ⁴⁰ in said tube and barrel, and adapted to be actuated by compressed air, a valve controlling communication between the chamber and tube, means including a trigger for opening said valve, and means for resetting ⁴⁵ the trigger actuated means and retracting said plunger within the tube for the purpose specified.

4. In a rifle of the character described, a barrel, a magazine, means for single feeding ⁵⁰ projectiles from the magazine into said barrel, a compressed air receiving chamber, a tube establishing communication between said chamber and barrel, a plunger mounted to slide within the tube and barrel, a valve controlling communication between the chamber and tube, trigger actuated mechanism for opening said valve, and means for resetting ⁵⁵ said trigger actuated mechanism and retracting the plunger to its inactive position, and including a bell crank lever, having one branch disposed in the path of movement of said plunger, a member carried by the plunger and adapted to engage said lever when the plunger is operated in one direction, and a movable finger adapted to engage the other branch of said lever and operate the latter to retract the plunger as described.

In testimony whereof I affix my signature.
MAXIMO GUIDOTE.
